UNITED STATES PATENT OFFICE.

ALFRED OESTERREICHER, DECEASED, LATE OF VIENNA, AUSTRIA-HUNGARY, BY LEOPOLDINE OESTERREICHER, WIDOW AND GUARDIAN, AND JULIUS KHU, CO-GUARDIAN, ASSIGNORS TO BRÜDER REDLICH & BERGER, OF VIENNA, AUSTRIA-HUNGARY, A FIRM.

ELECTRICAL COUPLING OF SIGNAL-ARMS FOR RAILWAYS.

1,113,819.

Specification of Letters Patent. Patented Oct. 13, 1914.

Application filed September 12, 1912. Serial No. 720,063.

To all whom it may concern:

Be it known that ALFRED OESTERREICHER, deceased, formerly a subject of the Emperor of Austria-Hungary, residing at Vienna,

5 Austria-Hungary, (LEOPOLDINE OESTERREICHER, a subject of the Emperor of Austria-Hungary, residing at Liesing, near Vienna, Austria-Hungary, widow and one of the legal heirs of said ALFRED OESTERREICHER and guardian of the minor children 10 of said ALFRED OESTERREICHER, and JULIUS KHU, coguardian of MARGARETHE OESTERREICHER and VALERIE OESTERREICHER, minor children, and the other legal heirs of said 15 ALFRED OESTERREICHER,) did in his lifetime invent certain new and useful Improvements in Electrical Couplings of Signal-Arms for Railways, of which the following is a specification.

20 This invention proposes an improved coupling between the signal arm and the mechanical operating gear of a semaphore, and it resides, briefly, in the insertion of an electrically-controlled locking bar into the signal-operating rod, which bar is locked when the current is "on," and is then brought into engagement with the connecting rod, forming, with the latter, a rigid system. When the current is "off," the said 25 bar is disengaged from the connecting rod, due to the release of the armature, thereby detaching the connecting rod and the signal rod from each other.

An embodiment of the invention is illustrated in the accompanying drawing, wherein:

Figure 1 is a side elevation of the improved semaphore coupling, showing the position of parts prior to operation, and 40 with the electro-magnetic circuit closed, the dotted lines indicating the positions assumed by the locking bar and the armature of the magnet when the latter is deenergized. Fig. 2 is a similar view, but showing the signal 45 in "line clear" position after operation, the magnet being energized. Fig. 3 shows the signal in a "danger" position and the magnet deenergized. Fig. 4 is a fragmental elevation at right-angles to Fig. 2; and Fig. 5 is a plan view of a detail.

In said drawing, M indicates a fixed electro-magnet, the armature A of which has a hinge or pivotal mounting c. To this arma-

ture are secured the terminals of the legs of a fork a, which straddles the signal operating rod S' and carries at its end a roller r. Rod S' is slotted longitudinally, as shown, to receive therein the shank of the locking bar R, the latter having a hooked lower end and being pivoted at the upper end of its shank, in the afore-mentioned slot, upon a cross-pin d. The lower portion of rod S' is slidably fitted in the bore of the tubular connecting rod S², this rod S² being provided at its upper end with a head w having a conical or beveled bottom face, and being connected by a pitman l, or the like, to a chain wheel K, which wheel rotates about the shaft or spindle D and is connected by the chain or wire cable k with the interlocking gear, (not shown).

The mode of operation is substantially as follows:—If, during the time that the magnet M is deenergized, the connecting rod S² is drawn downward by the rotation of wheel K, the engagement of head w on said rod with the terminal hook on the locking bar R will tend to force the latter outwardly of its slot in the signal-operating rod S', whereby the pressure exerted by the locking bar 75 against roller r consequent upon its outward movement will pull armature A away from said magnet, as indicated in dotted lines in Fig. 1. In this way, the locking bar is released from engagement with head w, and, 80 as the rotation of the said wheel continues, the connecting rod S² will move upon and relatively to the rod S' and the latter and the signal P will be unaffected, said parts remaining in the position represented in 85 Fig. 1. On the other hand, when the magnet becomes energized by the passage of the current through its windings, the armature A will be attracted, and, in moving inwardly toward said magnet, will force bar R into 90 the afore-mentioned slot, with the result that the hook on said bar is forced into engagement with head w. Accordingly, when the subsequent downward movement of rod S² takes place, the rod S' will likewise be 95 drawn downward and the signal P will be caused to swing upwardly into "line clear" position, the roller r preventing any outward movement of the locking bar from its slot. When the current is again cut off, the 100 weight of the signal will become operative,

and will produce an upward movement of rod S' and bar R, with the result that the latter is disengaged from head w in the manner originally stated, and is caused to move the armature away from the magnet. The signal then drops again, as indicated in Fig. 3. The interlocking gear may then be operated to raise rod S' until its head again reaches a position for engagement by the locking bar hook.

10 We claim as the invention of ALFRED OESTERREICHER:—

15 1. In a railway signaling apparatus, the combination, with a pivotally-mounted signal, and a signal-operating means; of a pair of inter-fitted rods movable independently of each other and connected, one to said signal, and the other to the said operating means; locking means carried by the first-named rod for releasable engagement with the other rod; and an electromagnet having a movable armature connected with the locking means, for engaging the latter with the said other rod when said magnet is energized.

20 2. In a railway signaling apparatus, the combination, with a pivotally-mounted signal, and a signal-operating means; of a pair of inter-fitted rods movable independently of each other and connected, one to said signal, and the other to the said operating means, the second-named rod having a beveled head; a locking bar pivoted to the first-named rod and having a portion arranged to

35 engage said head; and an electro-magnet having a movable armature connected with said locking bar, for moving the latter into position to engage said head, and for holding the same in such engagement, when said magnet is energized.

40 3. In a railway signaling apparatus, the combination, with a pivotally-mounted signal, and a signal-operating means; of a pair of inter-fitted rods movable independently of each other and connected, one to said signal, and the other to the said operating means, the second-named rod having a beveled head; a locking bar pivoted to the first-named rod; an electro-magnet having a movable armature; and a fork connected to said armature and straddling said first-named rod and said bar, said fork having a roller bearing against the latter for moving the same into position to engage said head and for holding it in such engagement, when said magnet is energized.

45 LEOPOLDINE OESTERREICHER,
*Widow of Alfred Oesterreicher, deceased, and one of the
guardians of Margarethe Oesterreicher and Valerie Oester-
reicher, minor children of said Alfred Oesterreicher,
deceased.*

50 JULIUS KHU,
*Coguardian of Margarethe Oesterreicher and Valerie
Oesterreicher, minor children of Alfred Oesterreicher,
deceased.*
